UNITED STATES PATENT OFFICE.

JOSHUA W. JONES, OF HARRISBURG, PENNSYLVANIA; COMMONWEALTH TRUST COMPANY, EXECUTOR OF SAID JOSHUA W. JONES, DECEASED, ASSIGNOR TO JONES COMPANY, OF HARRISBURG, PENNSYLVANIA. A FIRM COMPOSED OF JOSEPH R. JONES, OF PHILADELPHIA, PENNSYLVANIA, J. MILEY JONES, ROBERT ROSS JONES, AND JOHN PAUL JONES, ALL OF HARRISBURG, PENNSYLVANIA, AND WILLIAM D. JONES, OF NEW YORK, N. Y.

PAPER-WEIGHT, LETTER-CLIP, AND CALENDAR-PAD HOLDER.

1,172,606.

Specification of Letters Patent. Patented Feb. 22, 1916.

Application filed December 4, 1913. Serial No. 804,683.

To all whom it may concern:

Be it known that I, JOSHUA W. JONES, a citizen of the United States, residing at Harrisburg, in the county of Dauphin and 5 State of Pennsylvania, have invented a certain new and Improved Paper-Weight, Letter-Clip, and Calendar-Pad Holder; and I do hereby declare the following to be a full, clear, and exact description of the same, reference being had to the accompanying drawings, forming part of this specification, and to the figures and letters of reference marked thereon.

This invention relates to an article of 15 manufacture designed for use on flat top desks and in like situations and adapted to serve as a paper weight which may be conveniently moved about and placed on the papers to be held; as a clip for holding letters or papers in upright position on the desk, as, for example, when attention is desired to be drawn to them; and as a holder for a calendar pad, whereby the current date or dates in the current month will be always exposed to view. Incidental to the 20 uses of the device above referred to, it conveniently forms an effective advertising medium or medium for displaying advertising matter; thus adapting the article for free 25 distribution where the advertising matter will pay for the cost of production and render the device more attractive than would otherwise be the case.

In its essential characteristics the device 35 embodies a relatively heavy base portion having upwardly extending converging arms thereon which are resiliently held toward each other at their upper ends, one or both of said arms being provided with pad 40 holding means on its outer face and the construction being such that the ends of the arms themselves constitute the handle by means of which the device may be moved about or conveniently used as a paper 45 weight.

Referring to the accompanying drawings, Figure 1 is a perspective view, partly broken away, of an article of manufacture embodying the present improvements, in its preferred form. Fig. 2 is a similar view show-

ing a slightly modified construction of the article. Fig. 3 is a similar view showing still another modification.

Like letters of reference in the several figures indicate the same parts.

To adapt the device for a paper weight and to insure its being held in proper upright position, the base portion should be made relatively heavy and the points of contact with the supporting surface relatively widely spaced apart. With these considerations in mind the preferred construction embodies a relatively heavy base which is formed in two sections, conveniently, separate castings A and A' which are spaced apart the proper distance to afford rather widely separated points of support for the device, and each of these base sections is provided with a broad flat upwardly extending arm B, said arms at their upper ends being bent laterally or away from each other conveniently in the form of curls or enlargements B', thus adapting them for use, first, as a handle by means of which the device may be lifted and moved about on the desk, and, secondly, as a calendar or advertising pad retaining means to be presently described. The spaced base sections are connected together by a bridge piece or pieces preferably constituting a hinge connection, 60 whereby the two upwardly projecting arms will be held toward each other at their upper ends but may be readily separated by the insertion of papers between them, where the device is utilized as a paper clip for 65 holding papers in upright position on the desk, as, for example, where they are to be kept in view for special attention.

The bridge piece referred to may be formed integral with the metal of which the 70 upwardly extending arms are formed, for example, as shown at D. in Fig. 2, in which instance it is of less width than the said arms and consequently constitutes a flexible or yielding hinge connection between 75 the base sections, or, as shown in Fig. 3, where its effective width is still further reduced by a central opening E whereby its resiliency is increased. The preferred construction, however, is that shown in Fig. 1, 80

where the metal constituting the upwardly extending arms is extended inwardly at the lower edge a distance approximately one half the distance between the base sections, 5 as shown at F, and the edges of the inwardly extending portions are connected by a pintle hinge connection. The pintle is formed by a resilient wire, for example, a pair of twisted wires G, said pintle being 10 held under tension by having its opposite ends bent around to lie against the under side of the opposite sections F of the bridge portion of the structure. While the upwardly extending arms may themselves be 15 more or less resilient the main effective resiliency is secured by the yielding of the connecting bridge portion referred to and by the use of a plurality of twisted wires for the pintle, a very considerable range of 20 resiliency is permitted without danger of setting the metal of the arms or bridge, thus making the device one which cannot be easily destroyed or injured by widely separating the upper ends of the arms.

25 As a convenience in manufacture the arms may be united to the base sections by having the lower edge of the same clamped in slots H in the base sections, as shown in Figs. 1 and 2, or they may be held in recesses in said base sections by screws or rivets as shown at I, in Fig. 3.

The broad flat faces of the upwardly extending and converging arms are adapted to serve as pad holding faces, and for this 35 purpose are provided with pad retaining means, the retaining means preferably employed consisting of a pocket K formed in the base section at the base of the arm. The lower edge of the calendar pad may be inserted in the pocket or recess K and its upper edge in the recess formed behind the outwardly curled enlargement at the upper end of the arm. With this construction a number of cards or sheets constituting the 40 pad, say, one for each month in the year may be mounted in the said pockets or recesses and held firmly for ready reference. As is usual in calendar pads the cards may be printed on both sides, thus requiring but 45 six cards for the months of one year, and this number of cards may be held in the pockets without giving the arms the appearance of undue weight or thickness. The pockets or recesses in the base sections 50 limit the movement of the cards edgewise, no limiting stops at the upper ends being required. When it is desired to remove and shift the cards it is a simple matter to slip a finger behind them at an intermediate 55 point, bend them outwardly, so that the upper ends or edges are released, and after the proper card is brought to the top, reversing the operation for inserting them again into place.

60 65 The curled upper ends of the converging

arms and the surface of the base sections may be conveniently utilized for advertising matter, and the pad or cards held on one of the arms may be utilized for the same purpose, thus keeping constantly before the person on whose desk it is located a reminder of the advertiser, and making the device a medium for most effective advertising purposes.

Obviously, the particular form of the 75 base sections and detail construction of the device may be modified without departing from the present invention which contemplates in its broadest aspect a weighted base with upwardly extending converging 80 and resiliently held arms which, at their upper ends form a handle by which the device may be moved about, said arms provided with divergent end surfaces for assisting in the convenient insertion of papers 85 to be held upright in the device and pad holding means on the outer face of one of the arms, whereby not only are the papers to which attention is to be drawn held in conspicuous position, but they will be held 90 in such position without concealing the face of the pad. The weight of the papers in the clip rests on the bridge piece or hinge connection and tends to hold the upper ends of the arms closed on the papers.

Having thus described my invention, what I claim as new and desire to secure by Letters Patent of the United States, is:

1. A device of the character described, comprising a base having heavy side portions connected by a relatively light intermediate portion, and upwardly extending substantially flat plate members converging toward each other at their upper ends, said device embodying means for holding said plate members yieldingly in juxtaposition at their upper ends, one of said plate members having calendar pad holding means on its outer side.

2. A device of the character described, comprising a base embodying heavy side portions and an intermediate portion connecting the side portions, upwardly converging substantially flat plate members, said device embodying means for yieldingly holding said plate members in juxtaposition at their upper ends to form a paper clip, one of said plate members having a calendar pad edge receiving recess therein.

3. A device of the character described, comprising a base having a relatively light intermediate portion connecting its heavy side portions, upwardly converging substantially flat arms, said device embodying means for holding said arms yieldingly in juxtaposition at their upper ends, the upper ends of the arms being extended laterally to form a handle whereby the device may be lifted, the proximate faces of said lateral extensions being divergent to guide papers be- 120 125 130

tween the arms, one of said arms being provided with calendar pad holding means on its outer side.

4. A device of the character described comprising a heavy base formed of two parallel sections flexibly connected together, and an upwardly extending arm mounted on each of said base sections, said arms converging toward their upper ends to form a paper clip.

5. A device of the character described, comprising a heavy base formed of two parallel sections, an upwardly extending arm on each section, and a yielding connection 15 between said sections bridging the space between the base of the arms, whereby papers held between the arms will rest on said connection and tend to hold the ends of the arms closed.

6. A device of the character described comprising a heavy base formed of two parallel sections spaced apart and each having an upwardly extending arm, the said arms

converging toward their upper ends and a hinge connection between said base sections 25 bridging the space between the base of the arms and adapted when moved downwardly to move the ends of the arms toward each other.

7. A device of the character described, comprising an upwardly extending substantially flat plate-like member, said member being weighted at its lower extremity, another upwardly extending plate member, said members converging toward each other 35 at their upper ends, and connecting means intermediate said members, said device embodying means for holding said plate members yieldingly in juxtaposition at their upper ends, one of said members having a cal- 40 ender pad holding means on its outer side.
